UNITED STATES PATENT OFFICE.

JOHN WILLIAM DEAN, OF CRAGFORD, ALABAMA.

WIRE-STRETCHER.

1,234,297.

Specification of Letters Patent.

Patented July 24, 1917.

Application filed December 23, 1916. Serial No. 138,652.

To all whom it may concern:

Be it known that I, JOHN WILLIAM DEAN, a citizen of the United States, residing at Cragford, in the county of Clay and State of Alabama, have invented certain new and useful Improvements in Wire-Stretchers, of which the following is a specification.

This invention relates to certain new and useful improvements in wire stretchers.

10 An object of the present invention is to produce a simply constructed device for manipulating barbed, slick, mesh, or other forms of wire when adapting it to the use desired, and to that end comprises a pair 15 of arms pivotally connected at one end, each of said arms being provided with a clamp or dog reversibly positioned therein and adapted to coact with the base of a channel way for gripping the wire in uniform 20 alinement irrespective of the direction of pull.

Another object of this invention is the production of a light and durable wire stretcher including pivotally connected arms, 25 each of said arms being formed of detachable members and having engaging prongs arranged upon the ends and sides of said arms, and adapted for use whether the arms of the stretcher be used as a hinged pulling 30 unit or separated and used as single stretching elements.

A further object of this invention is the production of a stretching apparatus including a gang element provided with a 35 plurality of fastening devices to which the material to be stretched is attached, the said gang element being adapted to be connected with the clamps of the stretching apparatus and operable therethrough.

40 The invention further consists in the combination and arrangement of the several elements of construction hereinafter described and pointed out in the appended claims.

45 In the drawings,—

Figure 1 is a perspective view of my improved wire stretcher.

Fig. 2 is a side elevation thereof.

Fig. 3 is a view of my stretcher, illustrating the manner in which two free ends of wire are clamped therein for drawing them together.

Fig. 4 is a view showing the position in which the stretcher is placed when stretching a single wire, the free end of the wire passing beneath both clamping dogs for al-

ternately holding and gripping the wire in progressively pulling it.

Fig. 5 is a view of the stretcher illustrating the manner in which the stretcher is applied to a wire to remove bent or kinked portions.

Fig. 6 is an enlarged detail view, partly in section, of one of the clamps or dogs engaging a wire positioned on the base of the channelway provided in the arm of the stretcher.

Fig. 7 is a side elevation of one arm of the stretcher detached, and the gang element provided with fastening devices, shown as applied to a mesh wire for stretching the same uniformly.

Fig. 8 is a modified form of my stretcher in which the handles are made of wood and fitted with hinge and clamping elements of special construction.

Fig. 9 is an enlarged sectional view through one of the clamping elements as secured to a wooden arm, and

Fig. 10 is an enlarged perspective view illustrating the form of clamping element shown in Fig. 8.

The present invention has been designed for use in connection with stretching wire in the building of fences and the like, but it will be understood that it is equally useful in placing telegraphic wires, guy and rigging network, and the like.

Referring to the drawings, and more especially to Figs. 1 to 6, inclusive, the stretching device 1 comprises a pair of arms 2 and 3 pivotally connected at 4 by a detachable connection. The construction of stretcher shown in the figures just mentioned is of suitable metal having light and durable qualities.

The arms 2 and 3 are formed of outer hollow sections 5 and inner hollow sections 6. These sections are provided with suitable screw-threads, as shown, adapted to be fitted into the intermediate elements now to be described. While I have shown screw-thread connections for the hollow sections, it will be understood that various other forms of fastening means may be employed.

The intermediate elements to which the handle or arm sections are secured are indicated at 7 and 8, and comprise a body portion recessed at each end to receive the ends of the hollow sections 5 and 6, a slotted portion 9 and pivoted clamps or dogs 10. The clamps or dogs 10 are pivoted at 11 and are

adapted to abut against the base of the slotted or channel portion 12. These clamps are reversible, that is to say, they can be swung about their pivots clearing the opposite base or end wall 13 of the slotted portion.

As shown, these clamps or dogs cannot clear the base 12 of the slotted portion. The clamps 10 are loosely pivoted and are provided with wire-engaging faces 14 and 15 which terminate in a suitable shoulder 16, the radius of which, from the pivot 11, will not permit the clamp to clear the channel base 12.

15 The elements 7 and 8 are cut away as at 17 to allow the wire to be placed upon the base 12 and permit either face of the clamp or dog to rest thereon depending upon the direction of pull desired.

20 The advantage of these reversible clamps can be readily seen, in that the alinement of the wire, when gripped for stretching, is uniformly straight, irrespective of the direction in which the wire is to be drawn.

25 The pivotal members into which the hollow arms 6 are threaded, are indicated at 18 and 19, and, as shown, comprise lug and ear connections 20, the former being carried by the pivotal member 18 and the latter being provided on the member 19.

30 Groups of engaging prongs 21 and 22 are formed on the members 18 and 19 and serve the purpose of firmly positioning the stretching device against or into a suitable object 35 during the stretching operation. The angle indicated at 23 formed between these two groups of prongs, is found to be highly useful in effecting lateral or corner manipulations, as will be readily understood.

40 In Fig. 4 of the drawings the clamps or dogs 10 have been positioned to effect a pulling of the wire in the direction indicated by the arrow, that is to say, the engaging face 15 is swung against the wire gripping it securely against the base 12 of the channel or slotted portion (see Fig. 6). Movement of the arm 3 in Fig. 4, in the direction of the arrow, tends to firmly grip the wire between the face 15 and the channel base 12 until 45 the distance of stretching has been reached, or until a new hold upon the wire is desired. In effecting a new hold or gripping of the wire, the clamp or dog 10 of the element 7 is swung against the wire, and the clamp or 50 dog 10 of the element 8 is released, at which time the arm 3 is swung in the direction of the arrow indicated in dotted lines in Fig. 4 to take a new hold on the wire.

55 A considerable stretching distance can be covered by the alternate use of these clamping dogs, as will be readily understood.

60 In the setting of the clamps, as shown in Fig. 3 of the drawings, it will be seen that the movement of the arms 2 and 3 toward each other, as indicated by the arrows, will

effect a drawing together of the ends of the wire. This use of the device is highly advantageous in repairing broken wires, or in the initial drawing together of the same in making a connection.

65 The clamps or dogs 10 are reversely set in Fig. 5 to that of Fig. 3, and as shown will effect a pulling of the wire as the arms 2 and 3 are moved away from each other, as indicated by the arrows. This use is essential in the straightening of bent wire or the removing of distorted or kinked portions.

70 The stretching device as shown in Fig. 7 of the drawings comprises the stretching unit, or a single arm thereof (as shown), and a gang connecting element 24. This connecting member 24 includes a bar 25 to which is secured a plurality of fastening hooks 26. These hooks 26 are preferably of the snap type and are spaced and used according to the relative spacing of the mesh wire which is being stretched. Connecting cords 27 extend from the bar at points approximately in line with the fastening means, to a common connection 28, from which latter a flexible connecting member extends to be gripped by the clamps or dogs 10 of the stretching device. As will be apparent, this form of stretching apparatus is highly useful in connection with the positioning of all kinds of mesh wire requiring a uniform pull.

75 In the modified form of stretcher shown in Figs. 8, 9 and 10 of the drawings, the arms 2^a and 3^a are formed of single pieces 80 of material, preferably wood. These arms are cut away intermediate their ends to form the slotted portions 9^a. Fitted within these slotted portions at one end thereof are members 30. These members are preferably of 85 malleable or cast metal and are held in place by the screws 31.

90 Formed between the side walls 32 and 33, respectively, of these members 30 is a channel or base portion 34 into which is placed 100 the wire. The action of the faces 15 and 16 of the clamps or dogs 10 upon the wire against the channel base portion 34 is reversible, as heretofore described.

95 By this arrangement of an attachable fitting reduction in cost of production and repair is obtained. In this form the pivotal connection 4^a is also made of cast or malleable metal, and embodies like features of 110 economy in repair and production.

100 While I have shown and described a form of my invention best known to me at the present time, it will be understood that various other forms, arrangements, &c., in construction and manufacture may be resorted 115 to without departing from the scope of my invention.

105 From the foregoing it will be obvious that a readily handled and compact stretching device has been produced capable of effect- 130

ing many stretching operations in an efficient and desirable manner.

What I claim is:

1. A stretching device for wire comprising pivotally connected arms, wire-gripping members located intermediate the length thereof, said gripping members consisting of a body portion having a slotted portion therein, a wire-receiving channel-way formed in said body portion, and a clamp pivotally positioned in said slotted portion, said clamp consisting of oppositely disposed wire engaging surfaces terminating in an intermediate shoulder adapted to abut against the channel-way at either end thereof and to swing through the slotted portion at the opposite end to that of the said channel-way.
2. A stretching device for wire comprising pivotally connected arms, wire-gripping members located intermediate the length thereof, said gripping members consisting of a body portion having a slotted portion therein, a wire-receiving channel-way formed in said body portion, a clamp pivotally positioned in said slotted portion, said clamp consisting of oppositely disposed wire engaging surfaces terminating in an intermediate shoulder adapted to abut against the channel-way at either end thereof and to swing through the slotted portion at the opposite end to that of the said channel-way, and a group of angularly arranged engaging prongs carried by said arms for holding the stretching device in position.
3. A stretching device for wire comprising pivotally connected arms, wire-gripping members located intermediate the length thereof, said gripping members consisting of a body portion having a slotted portion
- therein, a wire-receiving channel-way formed in said body portion, and a pivoted clamp having oppositely arranged wire-engaging faces terminating in an intermediate shoulder adapted to abut against the channel-way at either end thereof.
4. A wire stretching device comprising a pair of pivotally connected arms formed of detachable sections, wire gripping members secured to said sections intermediate the length of the said arms, said gripping members consisting of a body portion having a slotted part therein and a cut-away portion leading to the slotted part, a wire receiving channel-way formed in said body portion, and a clamp having oppositely arranged wire-engaging faces terminating in an intermediate shoulder adapted to abut against the channel-way at either end thereof and to swing through the slotted part at the opposite end to that of the said channel-way.
5. A stretching device for wire comprising a wire gripping member having a slotted portion therein, a wire receiving channel-way in said gripping member, and a clamp positioned in said slotted portion consisting of oppositely disposed wire engaging surfaces terminating in an intermediate shoulder and adapted to abut against the channel-way at either end thereof and to swing through the slotted portion at the opposite end to that of the said channel-way.

In testimony whereof I affix my signature in the presence of two witnesses.

JNO. WILLIAM DEAN.
